US0D1055972S

(12) United States Design Patent (10) Patent No.: US D1,055,972 S
(45) Date of Patent: * Dec. 31, 2024

(54) DISPLAY SCREEN WITH GRAPHICAL USER INTERFACE

(71) Applicant: Airbnb, Inc., San Francisco, CA (US)

(72) Inventor: Gary Butcher, San Francisco, CA (US)

(73) Assignee: Airbnb, Inc., San Francisco, CA (US)

() Term: 15 Years

(21) Appl. No.: 29/838,027

(22) Filed: May 10, 2022

(51) LOC (14) Cl. 14-04

(52) U.S. Cl.

USPC D14/492

(57) CLAIM

The ornamental design for a display screen with graphical user interface as shown and described.

DESCRIPTION

The FIGURE is a front view of a display screen with graphical user interface showing my new design.

The peripheral dash-dot-dash lines illustrate a display screen or portion thereof and form no part of the claimed design. The dashed broken lines within the peripheral dash-dot dash lines illustrate portions of the graphical user interface which form no part of the claimed design.

1 Claim, 1 Drawing Sheet
